UNITED STATES PATENT OFFICE.

GEORGE L. PREBLE, OF LYNN, MASSACHUSETTS.

COUNTER FOR BOOTS AND SHOES.

No. 866,732.

Specification of Letters Patent.

Patented Sept. 24, 1907.

Application filed March 30, 1907. Serial No. 365,565.

To all whom it may concern:

Be it known that I, GEORGE L. PREBLE, a citizen of the United States, residing at Lynn, in the county of Essex and State of Massachusetts, have invented certain new and useful Improvements in Counters for Boots and Shoes; and I do hereby declare the following to be a full, clear, and exact description of the invention, such as will enable others skilled in the art to which it appertains to make and use the same.

10 This invention relates to heel stiffeners or counters for boots and shoes.

It has been customary heretofore in the manufacture of boots and shoes to form the heel stiffeners or counters from leather or leather board according to the 15 grade of boots or shoes being manufactured. The leather and leather board from which these counters are formed as well as the cements and pastes used in many cases in securing the parts of the stiffeners together is so affected by moisture either from the feet 20 or other sources that the counters frequently become distorted and broken down thus spoiling the appearance of the shoe and causing discomfort to the wearer. The action of the perspiration from the feet or of other moisture upon the leather or leather board also causes 25 an objectionable discoloration and rotting of the lining of the shoe at the heel. Although various attempts have been made to produce a stiffener which would be free from these objections none of the proposed stiffeners have, so far as I am aware, proved satisfactory 30 or met the approval of the manufacturers who continue to use the leather and leather board counters.

It is the object of the present invention to provide 35 a heel stiffener or counter which will be free from the objections above noted, which will retain its shape permanently under all conditions of use and wear, which will be strong and durable and at the same time be of such thinness as not to take up an objectionable amount of room in the shoe or detract from its appearance either internally or externally.

40 With this object in view the invention contemplates the provision of a heel stiffener or counter consisting of a thin sheet of celluloid or similar pyroxylin compound molded to the desired shape and a sheet of fabric or other suitable reinforcing material permanently 45 secured thereto by an intermingling of the celluloid with the fibers of the reinforcing material. This counter is light and serviceable, it is absolutely water proof, it is resilient and yet as stiff or stiffer than a high grade counter of sole leather, it can be incorporated in a shoe 50 in the ordinary manner and can be held securely and permanently in place by the usual fastening devices, the upper edge of the counter will always retain sufficient stiffness to cling tightly to the foot of the wearer, and the entire counter will retain permanently the 55 shape imparted to it during the molding operation.

The layer of reinforcing material may form either the outer or the inner surface of the counter. It is preferred however to have the reinforcing material on the outer surface of the counter and to provide the inner surface of the counter with a sheet or layer of cushioning material united to the celluloid in the same manner as the reinforcing material. This layer of cushioning material may also serve as a reinforce to the counter. In thus uniting the materials from which the counter is formed I dip the sheet of celluloid or other waterproof material in a chemical which will partially dissolve and soften the surfaces of the sheet and then apply the cushioning material and strengthening fabric to the opposite surfaces of the sheet. Owing to the plastic or semi-plastic state of the immediate surfaces of the sheet of celluloid the surfaces of the other materials become embedded in and intermingled with the celluloid thus uniting the parts into an integral whole. The parts may be thus united before or after they are cut into the proper form for molding. In 75 either case the blank made up of the united materials is molded into the proper shape while the waterproof material forming the stiffening body of the counter is at the proper temper.

The construction of the counter will be readily 80 understood from the foregoing and is illustrated in the accompanying drawings in which

Figure 1 is a perspective view of a counter embodying all the features of the invention in their preferred forms. Fig. 2 is a sectional view through the center 85 of the counter; and Fig. 3 is a view showing a blank before it is bent or molded.

As shown in the drawings the stiffening body of the counter or heel stiffener consists of a thin sheet 1 of celluloid or similar pyroxylin compound. The inner 90 surface of the counter consists of a cushioning material 2 such as flannel, felt, or leather, which is united with the stiffening sheet. This cushioning material serves to render the shoe more comfortable to the wearer and also protects the lining of the shoe against 95 wear. The stiffening body 1 is strengthened and rendered more tenacious by an outer covering of woven or other textile fabric 3 united therewith.

The stiffening sheet, cushioning material and strengthening material may be cut to proper shape 100 and then united, preferably in the manner already described, to form the blank shown in Fig. 3 or the materials may be first united and then the blank cut from the united materials. In either case the blank is bent or molded into the desired shape indicated in 105 Fig. 1 while the sheet 1 is at proper temper and retains this shape when the material becomes set. The heel stiffener or counter thus formed is rendered stiffly resilient at the base where rigidity is required by the flange 4 and at the same time is thin and 110

flexible at the top where flexibility and resiliency without rigidity is desirable. No paste or cement which may be affected by moisture is required and the stiffening material is unaffected by moisture or a 5 moderate degree of heat and the counter will therefore retain its shape and not become soft or liable to distortion from exposure to moisture, heat or any atmospheric conditions.

The nature and scope of the invention having been 10 indicated and a preferred form of the invention having been specifically described, what is claimed is:—

1. A heel stiffener for boots and shoes consisting of a thin sheet of celluloid molded to the required shape, and

a sheet of reinforcing material permanently secured thereto by an intermingling of the celluloid with the fibers of 15 the reinforcing material.

2. A heel stiffener for boots and shoes consisting of a thin sheet of celluloid molded to the required shape, a sheet of reinforcing material upon the outer surface of said celluloid sheet and a sheet of cushioning material 20 upon the inner surface of said celluloid sheet, said sheets being permanently united by an intermingling of the celluloid with the reinforcing and cushioning material.

In testimony whereof I affix my signature, in presence of two witnesses.

GEORGE L. PREBLE.
